UNITED STATES PATENT OFFICE

CLARA OGILVIE MACINNIS, OF NEW YORK, N. Y.

DESIGN FOR A BRUSH OR SIMILAR TOILET ARTICLE

Application filed September 16, 1932. Serial No. 44,872. Term of patent 7 years.

To all whom it may concern:

Be it known that I, CLARA OGILVIE MACINNIS, a citizen of the United States of America, residing at New York city, county of New York, borough of Manhattan, and State of New York, have invented a new, original, and ornamental Design for a Brush or Similar Toilet Article, of which the following is a specification, reference being had to the accompanying drawing, forming a part thereof.

I claim:—

The ornamental design for a brush or similar toilet article as shown.

CLARA OGILVIE MACINNIS.
